FEED DEVICE

James D. Anderson, Stamford, Conn., assignor to Burndy Corporation, Norwalk, Conn., a corporation of New York

Filed Mar. 18, 1957, Ser. No. 646,742

8 Claims. (Cl. 198—221)

My invention relates to a means for feeding strip material to devices which perform subsequent operations thereon and more particularly, to a means for feeding strip material into a device which, in turn, controls the feeder.

Heretofore, such devices have either been independent of the device which they fed or an integral part thereof. The former required an independent driving mechanism and was therefore very expensive for general use. The latter was too restricted and therefore impractical.

Accordingly, a primary object of the present invention is to provide an improved feeding device which is simple in construction, durable, and inexpensive in manufacture.

Another important object of the present invention is to provide a feeder which is operated by the device into which it feeds.

A further object of the present invention is to provide a feeding mechanism which can readily be adjusted for variations in the strip material being worked and variations in the devices into which it feeds.

Still another object of the present invention is to provide a feeding mechanism wherein the movement of the feeder is effected in a simple and efficient manner.

Still another important object of the present invention is to provide an improved feeding mechanism for feeding strip material into a die.

These and other objects of the invention are accomplished and new results achieved as will be apparent from the device pointed out in the claims and illustrated in the accompanying drawing wherein:

Fig. 1 is an end view of an embodiment of the feed device of the present invention;

Fig. 2 is a top plan view of the feed device of Fig. 1;

Fig. 3 is a side elevation of the device of Fig. 1; and

Fig. 4 is a sectional view taken through lines 4—4 of Fig. 2 in the direction of the arrows.

Referring now to the drawing, the feed device designated generally by numeral 10 consists of a lower bearing block 12 and an upper bearing block 14 which enclose slidable bolt 16 in groove 20 formed by said blocks (Fig. 4). Finger 22, for engaging the work, extends laterally of bolt 16 at one end thereof. Cam follower 26, also extending laterally off of bolt 16, extends through opening 24 formed by bearing blocks 12 and 14. Double acting cam 28 is moved up and down by the reciprocating motion of component 30, in this instance a die component.

Mounted on top of bearing block 14 is a friction device 32 which consists of pin 34 which passes through elongated slot 36 in bearing block 14. One end of pin 34 fits into circumferential groove 38 on feed bolt 16. The other end of the pin is secured to friction block 40 which is free to slide within groove 42 of friction block cover 44. Bearing strip 46 is mounted above friction block 40 in groove 42. Above the bearing strip a rubber pressure pad 48 is positioned. Bearing strip 46 im-

2

parts a frictional force to the friction block 40 opposing its sliding action.

The strip 50 to be fed into the press may consist of integrally formed connectors 52 having arms 54 which are engaged by the feed finger. The connectors are fed into a press where a pair of dies, not shown, cause the connector arms to be crimped about a conductor. Thereafter, the crimped connector is detached from the strip. Such a connector and die set is shown in my copending application Serial Number 633,409, now abandoned.

In operation, as die component 30 starts its downward stroke, double acting cam 28 moves cam follower 26 and movement is imparted to bolt 16. However, pin 34 and friction block 40 resist the retraction of bolt 16. Since there is slight resistance to the rotation of bolt 16 as compared to the resistance to its reciprocation, bolt 16 will rotate until cam follower 26 comes to a stop against feed block 12. This position is shown in dot-dash in Fig. 1. With the rotation of feed bolt 16 stopped, the bolt slides from the protracted position shown in dot-dash in Fig. 2 to the retracted position shown in solid line in Fig. 2. This completes the retraction stroke of feed device 10 during which finger 22 was first lifted out of engagement with strip 50 and then retracted while in the raised or cleared position.

Die component 30 having reached its downwardmost position now reverses. Bolt 16, being more free to rotate than slide, as hereinabove explained, rotates until cam follower 26 comes to a stop against block 14, shown in solid lines in Fig. 1. This action causes finger 22 to move downwardly to strip engaging position while still in the protracted position. With bolt 16 no longer free to rotate, it slides to the protracted position shown in dotted line in Fig. 2 by the action of cam 28 on cam follower 26. This completes the feed stroke during which feed finger 22 was brought into engagement with strip 50 and then advanced a full feed stroke.

On the next movement of die component 30, the cycle will repeat itself.

If it is desirable to transport the work in the opposite direction, the double acting cam 28 shown in Fig. 3 could be arranged with its slot oriented from the upper left to the lower right instead of as shown.

The feed strip is supported on the frame work 56 mounted on press base 58.

Adjustment to the end position of the feed finger for any basic feed finger travel is made by means of adjustment screw 60 operating through slot 62. This will lock cam 28 to die component 30 in the desired position.

The different feed length requirements may be compensated for by overtravel on the retract stroke, or the feed cam 28 may be replaced with a cam of another angle. The feed finger may easily be replaced with fingers of other configurations to meet any specific requirement of the feed strip.

I have thus described my invention but I desire it understood that it is not confined to the particular forms and uses shown and described, the same being merely illustrative, and that the invention may be carried out in other ways without departing from the spirit of the invention and therefore, I claim broadly the right to employ all equivalent instrumentalities coming within the scope of the appended claims, and by means of which the objects of my invention are attained and new results accomplished, as it is obvious that the particular embodiment herein shown and described is only one of many that can be employed to attain these objects and accomplish these results.

I claim:

1. A feed device for intermittently advancing material along a given axis comprising a feeder having a cam

follower associated therewith, a double acting cam for operating the cam follower and feeder, a feed finger connected to the feeder for engaging the material to be fed, frictional means for controlling the sliding action of the feeder, said feeder being freely rotatable about an axis parallel to said given axis while under the control of said frictional means to cause the feed finger to engage and disengage the material, and said feeder being contained in a bearing block provided with a lateral opening through which the cam follower extends.

2. A feed device for intermittently advancing material along a given axis comprising a feeder having a cam follower associated therewith, a double acting cam for operating the cam follower and feeder, a feed finger connected to the feeder for engaging the material to be fed, frictional means for controlling the sliding action of the feeder, said feeder being freely rotatable about an axis parallel to said given axis while under control of said friction means to cause the feed finger to engage and disengage the material and wherein the feeder is provided with a peripheral groove into which a pin extends connecting said bolt and friction means.

3. A feed device for intermittently advancing material along a given axis comprising a feeder having a cam follower associated therewith, a double acting cam for operating the cam follower and feeder, a feed finger connected to the feeder for engaging the material to be fed, frictional means for controlling the sliding action of the feeder, said feeder being freely rotatable about an axis parallel to said given axis while under control of said friction means to cause the feed finger to engage and disengage the material and wherein the friction means includes a friction block connected to the feeder through a slot.

4. A feed device for intermittently advancing material along a given axis comprising a feeder having a cam follower associated therewith, a double acting cam for operating the cam follower and feeder, a feed finger connected to the feeder for engaging the material to be fed, frictional means for controlling the sliding action of the feeder, said feeder being freely rotatable about an axis parallel to said given axis while under control of said friction means to cause the feed finger to engage and disengage the material and wherein the friction means includes a friction block, a bearing strip, and means for pressing the bearing strip to the friction block.

5. A means for conducting material in step-wise fashion to devices for performing subsequent operations thereon, comprising: means for producing a vertical reciprocating movement; a rotatable and reciprocable feeding mechanism mediate coupled to said vertical reciprocating movement means; means for imparting movement to said feeding mechanism; said means successively first solely rotating said feeding mechanism about an axis parallel to the movement imparted to said material and then solely reciprocating same, the means for successively first rotating and then reciprocating said feeding mechanism being

one and the same; the rotation engaging and disengaging the feeding mechanism and the material, the reciprocation advancing the material; and means for resisting the reciprocation of the feeding mechanism during the rotation thereof.

6. A means for conducting strip material in step-wise fashion to devices for performing subsequent operations thereon, comprising: means for producing a vertical reciprocating movement; a rotatable and reciprocable feeding mechanism mediate coupled to said vertical reciprocating means; means for imparting movement to said feeding mechanism; said means successively first solely rotating said feeding mechanism about an axis parallel to the movement imparted to said material and then solely reciprocating same along the axis of rotation; the means for rotating and reciprocating said feeding mechanism being one and the same; the rotation engaging and disengaging the feeding mechanism and strip, the reciprocation advancing said strip; and frictional means for resisting the reciprocation of the feeding mechanism during the rotation thereof.

7. A means for conducting strip material in stepwise fashion along a given axis to devices for performing subsequent operations thereon, comprising: a rotatable and reciprocable feeding mechanism; cam means for imparting movement to said feeding mechanism; said cam means successively first solely rotating said feeding mechanism about an axis parallel to said given axis and then solely reciprocating same; the means for rotating and reciprocating said feeding mechanism being one and the same; the rotation engaging and disengaging the feeding mechanism and the material; and means resisting the reciprocation of said feeding mechanism during rotation thereof; said resisting means including a linking member constrained to move in a direction parallel to said given axis and coupled to said feeding mechanism during its reciprocation and decoupled from said feeding mechanism during its rotation.

8. A feed device for intermittently advancing material along a given axis, comprising: a feeder having a cam follower associated therewith; a double acting cam for operating the cam follower and feeder; a feed finger connected to the feeder for engaging the material to be fed; said feeder being adapted to reciprocate along and to rotate about an axis parallel to said given axis; means resisting the reciprocation of said feeder during rotation thereof; said resisting means including a linking member constrained to move in a direction parallel to said given axis and coupled to said feeder during its reciprocation and decoupled from said feeder during its rotation to cause the feed finger to engage and disengage the material.
